DOCKING LIGHT

John F. Morse, Hudson, Ohio

Application May 9, 1946, Serial No. 668,518

5 Claims. (Cl. 240—26)

1

The present invention has as its object the provision of an improved lighting installation which will assist in the operation of all types of water-borne craft, particularly motor boats and similar power operated craft.

Boats of the type specified are usually equipped with searchlights as the sole means for illuminating the docking area when making a night landing, but a searchlight will throw areas not in its direct path in absolute blackness and thus hide obstructions close to the boat. The invention consists in providing mountings for flood-lights in the hull of a boat so that the lights may be set or adjusted to illuminate the area immediately around the boat which cannot be reached by searchlights on the deck. In the preferred construction a number of docking lights are set about the hull of the boat and may be controlled by appropriate circuits so that the pilot may illuminate the entire area adjacent the hull or selected parts so as to assist in bringing the boat to its berth without collision with piling or other obstructions lying at or near the surface of the water.

The drawings and description show the best known and preferred means for mounting a light of the type specified in the hull, it being understood, however, that the invention is not confined to the details set forth.

In the drawings:

Fig. 1 is a rear view of the embodiment which has been selected to illustrate the invention.

Fig. 2 is a section taken on the line 2—2 of Fig. 1. In this view the full lines show the light in direct horizontal position, while the dotted lines show a position in which it will ordinarily be adjusted for throwing the beams of light toward the water immediately around the boat.

Fig. 3 is a front view showing of the light.

In the drawings, the numeral 1 represents the side or hull of the boat. At the desired points, apertures 2 are cut out a short distance above the water line and in these apertures are set the flanged sockets or cradles 4 which support the several lamps.

Each socket has a central cylindrical portion 5 which is of somewhat greater depth than the thickness of the hull so that it projects for a short distance outwardly of the hull. On the rear, or inside of the boat, the socket is formed with an outwardly projecting flange which fits against the side of the boat. Clamping bolts 8 are passed through the flange 6 and through the hull, the heads of the bolts resting against a clamp ring 10 which surrounds the projecting portion of the

ring 4. When the clamping ring is drawn up tightly no water may seep through the bolt holes. The area around the socket is filled in with a caulking composition, indicated at 11.

At a point toward the rear of the cradle, there is provided a rib 12 forming a seat, the inner surface of which is machined so that it provides a frustro-spherical surface to receive the corresponding surface of the lamp holder 14. As indicated in the drawings, the holder 14 is in the form of a segment of a sphere of sufficient extent so that the holder may be set in any selected angular position to direct the rays of the lamp 15 toward the surface of the water, as shown by the dotted lines in Fig. 2.

The holder 14 is clamped in its adjusted position by a ring 18, the inner surface of which is also formed as the segment of a sphere and fitting snugly against the surface of the holder. The ring 18 is held in position by a number of bolts 20 which are threaded into the flange 6. A compressible gasket 21 is seated in a recess on the rear face of the socket 5 in position to be forced into sealing relation to the holder 14 by the inward movement of the ring 18 which is provided with an annular shoulder 22 which enters the recess for the gasket.

The inner edge portion of the holder 14 is screw-threaded to receive the screw-threaded clamp ring 24 which is provided with a flange 25 to hold the lamp in position. The outer edge of the flange bears against a cap plate 26 which, in turn, bears against a grommet 28 and holds it against a shoulder 29 on the ring 14. The grommet 28 is channeled to receive the widest portion of the lamp 30. A cover plate 32 attached to the clamp ring 24 by bolts 33 completes the assembly.

The lamp itself may be of any commercial type, but is preferably fitted with a fog-penetrating lens and a filament shield which eliminates scattered light above the beam. It will be noted that the light does not project outwardly of the hull so that it will not be accidentally damaged. A plurality of these improved docking lights arranged symmetrically about the hull will illuminate the entire circle of water about the boat at a distance of one hundred feet or more.

The docking light is a valuable aid to after-dark maneuvering of the boat, particularly in docking.

What is claimed is:

1. A docking light for installation through the side of a boat comprising a ring-shaped socket

having a depth of the order of the thickness of a boat hull, a flange on one extremity of the socket adapted to engage the inside of a boat hull, the socket having a frusto-spherical inner surface in the vicinity of the flange, a frusto-spherical lamp-holding member snugly fitted in complementary relation to the inner surface of the socket, and a retaining member having a frusto-spherical inner surface in continuation of the inner surface of the socket, resilient means between the retaining member and the socket deformable upon complete engagement of the retaining member, and means detachably securing the retaining member to the flange.

2. The invention of claim 1, the lamp-holding member lying behind the outer rim of the socket throughout a substantial range of angular adjustment of the lamp-holding member.

3. An illuminator for installation in the hull of a boat comprising a ring member having an axial extent sufficient to occupy the hull thickness of a boat, means surrounding the ring member and adapted to secure the same from the inside and outside of a boat hull, a frusto-spherical surface formed on the inner face of the said ring member, a lamp holder having an outer frusto-spherical surface mating with the said frusto-spherical surface in the ring member, and a clamp ring detachably secured to the rear of the said ring member and bearing against the lamp-holder, said frusto-spherical surface in the ring member having its forward limits spaced substantially rearwardly of the outer extent of said ring member, whereby the outer extent of said lamp-holder lies within the outer end of the said ring member throughout a substantial range of angular adjustment of the lamp-holder.

4. An illuminator for installation in the hull of a boat comprising a ring member having an axial extent sufficient to occupy the hull thickness of a boat, means surrounding the ring member and adapted to secure the same from the inside and outside of a boat hull, a frusto-spherical surface formed on the inner face of the said ring member, a lamp-holder having an outer frusto-spherical surface mating with the said frusto-spherical surface in the ring member, and means to clamp the lamp-holder in adjusted angular position in said surface, said frusto-spherical

ical surface in the ring member having its forward limits spaced substantially rearwardly of the outer extent of said ring member, whereby the outer extent of said lamp-holder lies within the outer end of the said ring member throughout a substantial range of angular adjustment of the lamp-holder.

5. In combination, a boat hull having a through opening above the water line, a ring member in said opening, protruding from the opening on one end thereof, and having a flange engaging the area around the opening on the other end thereof, a clamping ring surrounding the protruding portion of the ring, means securing the clamping ring and flange to the boat hull, a frusto-spherical surface on the inner face of the ring member, and having its extreme, outer portion lying substantially rearwardly of the outer extremity of said ring member, means having an outer, frusto-spherical surface mating with said frusto-spherical surface in the ring member and constituting a lamp housing, a member bolted to the said flange and adapted to contact the lamp housing to secure it in adjusted, angular position, and a resilient, water-sealing member engaging the lamp-contacting member, the said ring member and the lamp-holding member.
